UNITED STATES PATENT OFFICE

HARRY AULL, OF PHILADELPHIA, PENNSYLVANIA, ASSIGNOR TO FRIEDBERGER-AARON MANUFACTURING COMPANY, OF PHILADELPHIA, PENNSYLVANIA, A CORPORATION OF PENNSYLVANIA

DESIGN FOR ELASTIC WEBBING

Application filed November 16, 1927. Serial No. 24,144. Term of patent 14 years.

To all whom it may concern:

Be it known that I, HARRY AULL, a citizen of the United States, residing in Philadelphia, county of Philadelphia, State of Pennsylvania, have invented a new, original, and ornamental Design for Knitted Elastic Webbing, of which the following is a specification, reference being had to the accompanying drawing, which forms a part thereof.

In the drawing, showing my new design:

Fig. 1 is a plan view of the elastic webbing which is shirred when unstretched; and Fig. 2 is an edge view of the same.

I claim:

The ornamental design for elastic webbing, as shown and described.

In testimony of which invention, I have hereunto set my hand, at Philadelphia, on this 9th day of November, A. D. 1927.

HARRY AULL.
